UNITED STATES PATENT OFFICE.

ALFRED L. WILLIAMS, OF PHILADELPHIA, PENNSYLVANIA.

PUMP, ENGINE, AND THE LIKE.

Application filed February 20, 1926. Serial No. 89,596.

This invention relates to pumps, engines, and the like, of the kind disclosed in the patent of C. H. Varley, No. 1,560,624, Nov. 10, 1925. In these devices there is a displacing element designated as a displacer, mounted within an enclosing casing. Depending on whether the device is used as a pump or an engine, the displacer is either driven or drives so that all points of the displacer move within the casing in circles of similar diameter, the movement being termed "paracyclic" movement. The displacer is so mounted within the casing that in such paracyclic movement all points on the surface of the displacer come into proximity with corresponding points on the inner wall of the casing. Under some circumstances the displacer may contact with the inner wall of the casing so that the movement of the displacer may be said to produce a traveling zone of contact between the displacer and casing, although contact itself may be avoided, but there may be an extremely wide clearance between displacer and casing.

In the engine or pump as shown in the patent of Varley, above identified, the displacer is shown in one form as substantially the shape of a horseshoe, and it is mounted within a cylindrical casing into which extends a web serving as a partition. The web lies between the spaced ends of the displacer, and the end of the web occupies a portion of the open center of the displacer. A central drive shaft is employed which is at one end supported in a bearing formed in the end of a bolt, by which the cover plate for the casing is held in position, and this drive shaft, through suitable gearing, operates a pair of cranks which in turn, by their rotation, impart to the displacer its paracyclic movement. The operation of the device depends on the fact that the displacer in its movement approaches very closely to the inner face of the casing, and this zone of close approach or contact, as the case may be, travels throughout the extent of the inner face of the casing. In practice, the displacer itself does not actually contact with the casing, but carries packing blocks which makes such contact, these blocks being resiliently mounted and extending a slight distance beyond the face of the displacer.

While the engine or pump above described is suitable for many purposes, some difficulties may arise owing to the presence of the

packing blocks, which are spring-pressed to working position. It is desirable that these packing blocks be omitted, because of the greater simplicity of the manufacturing operation by which the displacer is made, and also because the packing blocks will wear and may not make a satisfactory contact after a period of use.

The present invention is directed to the provision of an improved construction of the engine or pump above briefly described, and it involves the use of a yielding connection between the cranks and the displacer, such that the displacer and the casing may be brought so close together at the region of contact that the necessity of providing packing blocks is avoided. Furthermore, the connection between the cranks and the displacer is such that although the displacer and casing in the traveling zone of contact have an extremely small clearance, yet in the event that foreign matter of any kind enters the casing, and lodges between the displacer and the casing at any point, the connection will yield so that the displacer will ride over the foreign matter without imposing an undue strain either upon the casing or the displacer.

In the accompanying drawings there are shown different views of the improved engine or pump, and

Fig. 1 is an elevation of one form of the device with the front cover plate and certain other parts removed,

Fig. 2 is a horizontal section on the line 2—2 of Fig. 1,

Fig. 3 is a sectional view on the line 3—3 of Fig. 1,

Fig. 4 is a sectional view through the connection between the crank and the displacer, but showing a modified construction,

Fig. 5 is a view similar to Fig. 1, showing a different construction,

Figs. 6 and 7 are sectional views on the lines 6—6 and 7—7 respectively of Fig. 5, and

Fig. 8 is a detail view in elevation of another modified form.

Referring now to the drawings, the device is seen to consist of a casing 10, mounted on a base 11, this casing being of generally cylindrical form. The casing is provided with a central web 12, and is closed by front and rear cover plates 13 and 14 respectively. The displacer 15, which is of

horse-shoe shape, is enclosed between the central web 12 and the front cover plate 13, these parts forming the outer working face for the displacer. An inner working face 5 is provided by a cylindrical boss 16, carried by a web 17, the latter acting as a partition which divides the two sides of the casing into intake and exhaust chambers. The front cover plate 13 is secured to the 10 central web by a bolt 18, carrying a nut 19, the inner end of the bolt 20 being recessed to receive the forward end of the drive shaft 21.

Combined driving and guiding means for 5 the displacer are illustrated at 22, and consist of small auxiliary shafts carrying discs 23 from the forward faces of which extend square pins 24. The auxiliary shafts are mounted in suitable bearings formed in the central web and are packed by packing glands generally designated 25. To the rear of the central web the main shaft carries a pinion 26, meshing with similar pinions 27 and 28 on the auxiliary shafts 22.

25 The displacer is provided with a circular aperture 29 in either arm, in which is placed a circular bushing 30 having a rectangular slot in which is received the square pin 24. The bushing 30 terminates at its 30 outer end in a round portion or pin 32, which is centrally placed and extends beyond the end of the displacer and lies within the cavity 29. On this pin is mounted a bushing 33. A stout coil spring 34 lies 35 in the slot 31 and bears at one end against the end of the slot and at the other against one face of the pin 24. This spring is under compression so that the bushing will be moved by the spring as far to the right as 40 possible, as shown in Fig. 1. Thus the bushing is held eccentric to the pin 24 by means of this spring, but its eccentricity depends on the extent to which the spring is 45 collapsed. A spring 35, one end of which enters a vertical channel 36 in the displacer, bears at its lower end against the bushing 33 encircling the pin 32, and this spring supports the displacer with respect to the bushing 30.

50 With the construction described, it will be seen that as the shafts 22 are driven from the main drive shaft 26, the bushings 30 which are held in eccentric relation to the pins 24 by means of the springs 34, will cause the displacer to have a paracyclic movement, and the extent of this movement will depend on the length of the slot 31 formed in the bushing 30. The bushing is normally held by the spring 34, so that the 55 square pin 24 will lie at the extreme end of the slot and in this position the parts may be constructed so that there is a minimum clearance at the points 37 and 38, between the faces of the displacer and the bushing 60 and inner face of the casing respectively.

Should any foreign matter lodge on the inner face of the casing, or in any other way get between the face of the displacer and the face of the boss or the casing at the point where contact is to occur, the springs 70 34 may yield, thus reducing the eccentricity of the bushing and permitting the displacer to ride over the foreign matter. As soon as the foreign object has been passed, the spring will act to move the bushing and 75 with it the displacer, to its normal position with reference to the casing and boss.

It will be seen that if the pins 24 rotate for example, counter-clockwise, as shown in Fig. 1, when the movement has passed 80 through 90°, the springs 34 will be in the vertical position, so that if no spring 35 were employed, the weight of the displacer would rest entirely on the spring 34, and the weight of the displacer would therefore 85 cause the springs 34 to collapse to some extent and thus reduce the eccentricity of the bushing, and in turn vary the clearance between the displacer and the stationary parts. This would be undesirable, and in 90 order to overcome it, the springs 35 have been made use of, these springs always lying in the vertical position and always acting to support the weight of the displacer. These springs bear on the bushings 33 which are loose on the pins 32 and the pins being disposed centrally of the bushings have only a slight radius of circular movement as the displacer is moved by the bushing. The springs therefore always occupy a substantially vertical position. The springs are relatively weak, so 95 that when the two sets of springs 34 and 35 are opposed, the springs 35 may be collapsed by the force of the springs 34, so that the eccentricity of the bushing is not reduced thereby.

100 In Fig. 4 a somewhat modified arrangement is illustrated, although the purpose served is the same as that above described. Here the auxiliary shaft 22 terminates in a portion 39 which has a bore 40 formed through it, through which extends a pin 41. The ends of this pin enter openings in the 105 walls of the bushing, and the pin has a free fit in the bore 40. A spring 42 encircles the pin 41 and tends to hold the bushing eccentric with relation to the pin 40 so that the same action is produced as before. The bushing is driven by the engagement of the pin 41 in the bore 40, and is held eccentric with relation to the pin 39 by the spring 42.

110 In Fig. 5 there is shown a somewhat modified form of construction which serves the same purpose as in the construction previously illustrated. In this arrangement the disc 23 is provided with an eccentric pin 43 which lies within a recess 44, formed in the displacer. A link 45 is freely connected 115 to the pin 43 at one end, and at its other 120 end to the displacer. The eccentric pin 43 125 and the link 45 are so constructed that as the displacer moves, the eccentric pin 43 is caused to move in a circular path, so that the eccentric pin 43 and the link 45 130

to a pin 46 carried by the displacer. With this arrangement it will be seen that the rotation of the crank causes the displacer to be moved with the usual paracyclic movement, but that a pressure is exerted against the face of the boss 16 at the point 47. This pressure is a proportion of the load at right angles to the crank arm, and depends on the angle between the axis of the crank arm and the axis of the link, which may be called the angle θ . Should any foreign substance lodge between the inner face of the displacer and the boss at the point 47, the displacer may swing about the pin 43 and ride over the obstruction, and the amount which the displacer will swing will depend on the length of the link 45. By constructing this link of proper proportions it is possible to construct the pump so that there is ordinarily a small clearance between displacer and casing or boss; but this clearance may be increased as may be required to permit the moving parts to ride over foreign matter which has entered the device. After riding over the obstruction, the displacer will be restored to normal position by reason of the resistance opposed to the displacer movement by the fluid which is being pumped.

In Fig. 8 there is shown a different form of connection between the displacer and the driving mechanism. In this construction the displacer has an opening 48, in which is received a crank pin 49, extending from the disc 23, and the hole 48 is made somewhat larger than the pin. The crank pin is constructed to describe a circle of larger diameter than it is possible for the displacer to follow, due to contact with the walls of the casing. In the revolution of the crank pins they exert a pressure on the displacer which is not at right angles to the cranks, but is in a direction such that there is a component toward the nearest part of the casing. The presence of foreign material between the displacer and the casing will cause the displacer to move relatively to the cranks, due to the loose fit of the crank pins in the holes in the displacer, but such a change in position results in increasing the component of the force exerted by the pin on the displacer and directed so as to force the displacer toward the casing. The greater the obstruction, the greater will be the force exerted on the displacer in a direction toward the casing, but owing to the freedom of movement of the displacer relative to the pins, a considerable clearance between displacer and casing is permitted so that the displacer will ride over ordinary obstructions without causing damage either to the cranks, the displacer, or the casing. The displacer is normally supported in the position illustrated in Fig. 8, in which the crank bears against the lower side of the opening in the displacer by reason of the

resistance of the fluid being pumped. This prevents the displacer from dropping down so that it would rest on top of the pin.

Wherever the phrase "traveling zone of contact" appears, either in the specification or the accompanying claims, it is intended to include the close approach of the displacer to the casing, even though no actual contact occurs.

I claim:

1. An engine or pump of the kind described, comprising a displacer element entirely enclosed and adapted to be displaced within a chamber in such manner as to maintain a traveling zone of contact with the walls thereof, the chamber having inlet and outlet ports, crank members connected to the displacer element, a yielding connection between the crank members and the displacer, these crank members being adapted to rotate and also to guide the displacer in such manner that all points thereof move in circles of similar diameter, and the yielding connection permitting a variation in the diameter of the circles last mentioned.

2. An engine or pump of the kind described, comprising a displacer, a casing enclosing said displacer, inlet and outlet ports in the casing, a rear cover plate, a central web, a drive shaft, a pair of crank members disposed between the cover plate and the central web and driven from the drive shaft, and a yielding connection between the displacer and the crank members such that the rotation of the crank members by the drive shaft imparts a paracyclic movement to said displacer the amplitude of which may be varied.

3. An engine or pump of the kind described, comprising a displacer element entirely enclosed by and adapted to be displaced within a chamber in such manner that every point on the displacer moves through a circle of the same diameter, the chamber having inlet and outlet ports, a pair of driven crank members, and a connection between the crank members and the displacer by which the diameter of said circles through which the points on the displacer move may be varied.

4. An engine or pump of the kind set forth, comprising a casing having a central web and a front cover plate forming a chamber, inlet and outlet ports in the casing, a drive shaft, a pair of auxiliary shafts driven by the drive shaft, a displacer element lying in the chamber, bushings in the element, and yielding means mounted between the bushings and the auxiliary shafts by which the bushings are held eccentric to the shafts and serve to impart a paracyclic movement to the element as the shafts are rotated.

5. An engine or pump of the kind set forth comprising a casing having a central

- web and a front cover plate forming a chamber, inlet and outlet ports in the casing, a drive shaft, a pair of auxiliary shafts driven by the drive shaft, a displacer element lying in the chamber, bushings mounted in the element and provided with slots, extensions from the auxiliary shafts entering the slots and having a driving connection with the bushings, and means in the slots for holding the bushings eccentric with relation to the shafts whereby the rotation of the shafts imparts a paracyclic movement to the element through the bushings.
6. An engine or pump of the kind set forth, comprising a casing, inlet and outlet ports in the casing, a displacer element in the casing, driven auxiliary shafts mounted in the wall of the casing and having a driving connection with the element, means carried by the shaft and having a variable eccentricity for imparting a paracyclic movement to the element, and means interposed between the shaft and the element for yieldingly supporting the element with relation to the shaft.
7. An engine or pump of the kind set forth, comprising a casing, inlet and outlet ports in the casing, a displacer element in the casing, a pair of driven shafts mounted in the wall of the casing, these shafts having

portions of square cross section, circular bushings mounted in the displacer and provided with rectangular slots into which the square portions of the shafts are received, springs in the slots holding the bushings eccentric to the shafts whereby the rotation of the shafts will impart a paracyclic movement to the displacer element through the bushings, and yielding means disposed between the displacer and the shafts for supporting the displacer relative thereto.

8. An engine or pump of the kind set forth, comprising a casing, inlet and outlet ports in the casing a displacer element disposed therein, a pair of shafts mounted in the wall of the casing, these shafts having portions of square cross section, a pair of bushings mounted in the displacer and provided with rectangular slots in which the square portions of the shafts are received, springs lying in the slots and bearing against the shafts and bushings to hold the bushings eccentric to the shafts whereby upon rotation of the latter the displacer will be given a paracyclic movement within the casing, extensions from the bushings, and springs supporting the displacer and bearing on these extensions.

In testimony whereof I affix my signature.
ALFRED L. WILLIAMS.
